MINERAL BLOCK FOR A BIRDCAGE

Edgar F. Bailey, Boonton, N.J., assignor to Hartz Mountain Products Corporation, New York, N.Y., a corporation of Delaware

Filed July 7, 1967, Ser. No. 7,729

Term of patent 14 years

(Cl. D1—27)

FIG. 1 is a perspective view of a mineral block for birdcages, showing my new design.

FIG. 2 is a front view thereof.

FIG. 3 is a side view thereof.

FIG. 4 is a top view thereof.

FIG. 5 is a bottom view thereof.

Both side views are identical. The rear of the block is plain.

The broken lines representing the fragmentary portion of the birdcage in FIG. 1 are shown for illustrative purposes only.

I claim:

The ornamental design for a mineral block for a birdcage, as shown and described.
